UNITED STATES PATENT OFFICE.

DANIEL O. LOY, OF MONTICELLO, ASSIGNOR TO THE AMERICAN PAVEMENT COMPANY, OF CHICAGO, ILLINOIS.

INTERLOCKING TILE OR PAVING-BLOCK.

SPECIFICATION forming part of Letters Patent No. 392,277, dated November 6, 1888.

Application filed May 11, 1887. Serial No. 237,837. (No model.)

To all whom it may concern:

Be it known that I, DANIEL O. LOY, a citizen of the United States, residing at Monticello, in the county of Piatt, State of Illinois, have invented certain new and useful Improvements in Interlocking Tile or Paving-Blocks, of which the following is a specification, reference being had therein to the accompanying drawings.

10 This invention relates to the construction of bricks or blocks designed for use in making various structures—such as road-beds, pavements, street-crossings, sewers, culverts, and any and all others to which the invention may 15 be applied; and it has for its general object the construction of such structures from or by the use of blocks that are adapted by their conformation and various arrangements to interlock and interbind, so as to render any 20 structure in which they are employed readily made, and, if desired, unmade and remade, readily repaired, and when made staunch, strong, and serviceable.

Other objects and advantages of the invention 25 will appear in the following description, and the novel features thereof will be particularly pointed out in the claims.

Referring to the drawings, Figure 1 represents an arched road and street-railway bed 30 constructed of blocks made in accordance with my invention. Figs. 2, 3, 10 to 21, and 23 represent different forms of blocks embodying essential features of my invention. Figs. 4 and 5 represent flat road and street-railway 35 beds, curbs, and sidewalks formed of blocks constructed in accordance with my invention. Fig. 6 represents a street-crossing and an oval sewer or culvert, and Fig. 7 a circular sewer or culvert in cross-section, made of my improved blocks. Fig. 8 represents a two-layer 40 road-bed having an asphalt or other surface. Fig. 9 is a section of a horizontally-curved road and street-railway bed; and Fig. 24 is a modified arrangement of blocks in a street- 45 railroad bed, all involving in their make-up a use of my improved blocks. Fig. 22 is a modified manner of completing the interlocking of my blocks.

It is well known that burned brick, while 50 cheaper than cut stone, is full as serviceable as stone, and that for the structures hereinbefore

specified and hereinafter mentioned the same would be preferable if it were possible to lay the same in such a manner as to render it staunch, strong, and stable. I have devised a 55 form of brick or block which may be applied successfully to the desired uses, and by slight changes, all involving a common principle of construction, said blocks, together with their properly-constructed and relatively-arranged 60 companions, may be utilized for the purposes herein specified. As strength alone is required in the hidden parts of certain structures, cheaper coarser clay may be employed in the hidden parts than in the exposed portions, 65 thus further contributing to the cheapness of roadways and other structures, which are usually very expensive.

The principle involved in this invention is the provision of blocks which, when used in 70 structures of either two, three, or more layers, shall co-operate with each other in such manner as to interlock and form a bond against separation in any and all directions necessary to resist the stress, strain, weight, or load naturally brought upon the structure.

A, Fig. 2, represents one of my blocks, and it is provided with one or more projections, A', which are preferably arranged directly at a corner or the corners of the block. C, Fig. 3, 80 represents a bottom and plan view, respectively, of a companion block, and is provided with a recess, C', adapted to receive the projection or projections A' of the block A. The blocks are provided with openings A² C², respectively, for a purpose hereinafter described. Now, taking these two blocks A and C—that is, taking a number of blocks some of which are like the block A and others like the block C—it will be seen, as hereinafter fully described, that various arrangements of the same may be made to produce different structures in which the blocks employed may be locked together and bound against displacement. For example, several blocks having a projection, A', at a corner may be arranged so as to bring the projections of the several blocks adjacent to each other, and the block C may be placed thereon or thereunder when the projections depend or are located upon the under 90 surface of the block, so that the several blocks A will be bound together against displacement.

by the block C, and this without regard to the remaining outlines of the several blocks A. In other words, it is not absolutely essential that the block A should be rectangular or square, or that it should have more than one projection in order to be capable of being assembled and bound and interlocked with others of its kind by means of the block C.

In laying structures comprising two or more layers by arranging the blocks in courses, as clearly illustrated in Fig. 1, it is apparently preferable to provide each of the blocks A with a projection, A', at each of its corners and to make the recess C' of the block C of such conformation and proportion as to receive and retain the projections of the adjacent blocks A.

Now, simply for the purpose of clearness of a description of my invention I shall designate the block A as a "binding-block" and the block C as a "surface-block," and will state that the under surface of the binding-block is, when intended for use in an intermediate layer, provided with lateral ribs, flanges, or projections A³, extending from end to end of the block. It is also apparent that these ribs A³ may be removed centrally and transversely of the block, so as to produce a double set of projections A', so that a surface-block may be employed at opposite sides of the binding-block whenever desired.

Ordinarily the lower layer of a structure comprises blocks B, which are provided upon their upper surfaces with lateral flanges or ribs B', so as to form a central groove, trough, or recess, B³, the side walls of which may be either vertical, outwardly beveled, or dovetailed, as desired. With such a lower layer it is a simple matter to assemble a series of binding-blocks, A, as represented in the various examples of road-beds illustrated, so that the projections or ribs A³ shall rest within the recesses of adjacent base-blocks B, and thus serve to bind the same together. Upon the blocks A, I then place the surface-blocks C, which receive the projections A' of four binding-blocks.

Now, the importance and advantage of the openings C' A' are apparent, in that asphalt, cement, or any other suitable composition may be run into and through the said openings in the surface-blocks down upon and, in case of a three-layer structure, through the binding-blocks and into contact with the base-blocks, and thus the same are firmly cemented into a solid mass. The principle of binding, locking, and cementation is present in a structure involving only two layers, as illustrated in Fig. 8, in which case I may also provide openings C' at the sides of the block, and these may or may not register with similar openings in the sides of the adjacent blocks, so that the composition shall further increase the locking functions of the several blocks embodied in the structure. A covering, I, of asphalt or other suitable composition, may be placed upon the structure, if desired.

I have stated that the walls of the groove

B³ in the base-block, and therefore the corresponding walls of the companion block ribs or projections, may be either straight, outwardly inclined, or dovetailed, straight walls being shown at the left of Fig. 1, outwardly-inclined walls at the right of said figure, and dovetailed walls in Fig. 4. In Fig. 22, however, I have shown a form in which the dovetail function is not accomplished until the filling has been run through the openings C' of the surface-blocks.

The introduction of the filling between the base and surface blocks serves to complete the dovetail joint between them, because the channel of the one, although bounded by inwardly-inclined side walls, is sufficiently wide to freely pass down over the head formed by two adjacent ribs of the base-blocks; but when the cementation or other filling composition, b, is run into the joint the same becomes in reality a dovetail joint, as is apparent upon an examination of said Fig. 22.

Instead of introducing the cement or other binding composition through the aperture C, the blocks C may be constructed with a space between them into which the composition may be run, as shown at b', Fig. 22.

In Fig. 1 an arched road-bed or structure is shown, while in the remaining figures similar structures are represented as flat. The arch, it is apparent, is readily produced by curving each block upon a desired circle, so that a series of them when placed together shall produce the desired arch or curve, and this curvature of the blocks and of the completed structure may be extended to produce either oval or circular structures, as in sewers, culverts, &c., as illustrated in Figs. 6 and 7.

It now remains to produce the structure curved in a horizontal plane—as, for example, at street-corners and in street and other railway road-beds. This form of structures involves merely the tapering of the several blocks employed upon radial lines agreeing with the circle of the curve. A block detached is represented in bottom view in Fig. 23.

There are various manners of arranging blocks constructed in accordance with my invention in road-beds where it is desired to make provisions for the rails, and it may be the ties I of a street-railway, and in such cases I may place the rail G and its stringer G' upon either the foundation-blocks B, as in Fig. 9, having removed its rib B', or longer base-blocks B B may be employed having opposite ribs B', as in Fig. 21, or the stringer G' may be of less depth and filling pieces or material, G³, inserted, as shown at the right of Fig. 4. Approach pieces or spaces G³, Fig. 1, may be employed between the blocks C of the road-bed proper and the rails and stringers of the railway, and also at street-corners and other desired places approach-blocks D may be employed, the object and purpose of these blocks being to render the passage of vehicles upon the road-bed from adjacent surfaces more easy than would be the case if the outline of the

blocks D were angular. This ease of approach is produced by simply rounding the corners D' of the block, as shown at Figs. 1 and 6. The approach-blocks D are preferably extended in length, so as to overlap one and a portion of an adjacent binding-block A, in order to lock the structure against displacement of the several blocks going to make up the same. As shown in Fig. 1, the approach-block D has an extension, D², beyond the depending rib D³, so that while the rib D' at the edge thereof makes connection with one of the binding-blocks A, the rib D³ thereof completely fills the channel of the adjacent binding-block, or, in other words, the rib D³ is twice the width of the rib D', and in this manner the approach-blocks are bound to the binding-blocks.

As illustrated at the left of Fig. 4, the binding-blocks and base-blocks may be carried into a vertical series to produce a curb, and this either by placing them flatwise upon each other or edgewise. This latter arrangement is illustrated in Fig. 5.

Whenever the surface-blocks are employed between the rails of a railway, they may be provided with a corrugated or ribbed surface, as shown at C², Figs. 4 and 14, and the surface-blocks themselves may, if desired, be made of fire-clay, in order to render them capable of withstanding the rough usage to which such road-beds are subjected.

In addition to the edge locking apertures or grooves C², I may, if desired, provide longitudinal grooves C³ to receive the filling composition and assist in binding adjacent blocks together. In Fig. 19 I have shown a block having ribs C² upon one side to fit into similar channels or grooves upon the adjacent side of a similar block, so that when laid in series they become locked together.

In Figs. 10 and 14 I have illustrated longitudinally-disposed openings, the principal purpose of which is to facilitate burning the block or brick in the kiln.

I have illustrated a few of the many uses to which my invention may be applied, but I may mention that it may be used as paving for streets, both in roadways and sidewalks, for crossings, for floors and walls of buildings, for curbs, copings, street-railway beds, culverts, sewers, arches, railway-curves, and either with or without suitable ornamentation the same may be employed to great advantage as borders to flower-beds, walks, and other similar structures.

Having fully described my invention, what I claim is—

1. A block having a projection at a corner thereof, in combination with similar blocks arranged with the projections adjacent to each other, and with a covering-block having a recess for receiving the adjacently-arranged projections, and also having openings for the introduction of a binding composition, substantially as specified. 65

2. The combination of a block having projections at opposite surfaces, on one surface at its corners, with similar blocks arranged with the corner projections adjacent to each other, base-blocks provided with recesses to receive one series of projections, and a covering-block having a recess to receive the other series of projections, substantially as specified. 70

3. The combination of a block having projections at opposite surfaces and openings 75 passing therethrough, with similar blocks arranged with the projections adjacent to each other, base-blocks provided with recesses to receive one series of projections, and a covering-block having a recess to receive the other 80 series of projections and provided with openings for the introduction of a binding composition, substantially as specified.

4. The combination of base-blocks having flanges, surface-blocks having recesses for 85 overlapping said flanges, and a stringer and rail arranged between and so as to properly space the surface-blocks, substantially as specified.

5. The combination of base-blocks having 90 ribs, binding-blocks arranged thereon and having projections, surface-blocks fitting the projections of the binding-blocks and spaced from each other, a stringer and rail, and an approach-block, the whole bound together, substantially as and for the purpose specified. 95

6. The binding-block A, having the projection A', apertures A², and ribs A³, substantially as specified.

7. The combination of the base-blocks B, 100 binding-blocks A, surface-blocks C C, stringers G', and rails G, substantially as specified.

In testimony whereof I affix my signature in presence of two witnesses.

DANIEL O. LOY.
